UNITED STATES PATENT OFFICE.

JOSEPH H. LOWDEN, OF ELYRIA, OHIO.

LIQUID RECEIVING AND CONVEYING DEVICE.

Application filed August 14, 1923. Serial No. 657,462.

To all whom it may concern:

Be it known that I, JOSEPH H. LOWDEN, a citizen of the United States, residing at Elyria, in the county of Lorain and State 5 of Ohio, have invented certain new and useful Improvements in Liquid Receiving and Conveying Devices, of which the following is a specification.

This invention relates to liquid receiving 10 and conveying devices, and particularly to such a device for use in garages, or at filling stations and similar places, for catching oil as it is drained from the engine of an automobile.

15 The objects of this invention include the construction of a device capable of being moved at will in a horizontal plane to the desired position under a liquid discharging receptacle, as the engine of an automobile, 20 and which is adjustable vertically to be maintained the desired distance from the receptacle.

Other objects will appear and be pointed out in the following specification, in which 25 a device constructed in accordance with my invention is disclosed.

In the drawings attached to and forming a part of this specification,

Fig. 1 is a top plan view of my invention 30 as applied to an oiling platform for an automobile;

Fig. 2 is a side elevation, partially in section, taken on line A—A of Fig. 1;

Fig. 3 is a sectional view similar to that 35 of Fig. 2 illustrating the container in raised vertical adjustment;

Fig. 4 is a side elevation of the device detached from the tracks.

In the drawings, a movable frame is composed of angle iron side members 2 having 40 the flange portions extending upwardly, and angle iron ends or cross members 3 with the flanges extending downwardly. To the depending flanges of member 3 are secured wheels 4 adapted to seat on substantially parallel tracks or runways 5 upon which the frame 1 may thus be moved. Tracks 5 are supported by brackets 6 which hook over the top of, or are otherwise suitably secured to 45 members 7 comprising a part of an oiling platform such as is commonly employed at filling stations.

It will of course be obvious that instead 50 of securing brackets 7 to the draining platform as illustrated in Fig. 2 they might equally well be elongated sufficiently to ex-

tend to and be supported by a superstructure above the top of an automobile. Side members 2 and end members 3 of frame 1 are preferably braced at the corners as by 60 plates 9 (Fig. 1) so that the frame is strong, rigid and not easily distorted in use.

Mounted upon the frame 1 to move lengthwise thereof is a carriage comprising angle iron side members 10, each having the 65 flange turned downwardly and each carrying in the flange one or more wheels 11 adapted to support the carriage movably on side members 2 of the frame. These side members 10 are secured together at the ends 70 by a plate 12 which extends thereacross and projects beyond one side thereof at 13. The projecting portion of the plate is provided with openings 14 of various sizes in which the operator can hang tools, such as 75 wrenches. The plate 12 is also provided with an opening 15, which is preferably annular in shape to receive a liquid receiving vessel or bucket 16, which is supported upon the plate by a flange 17 extending outwardly 80 from the top thereof. Suitable handles 18 are secured to the top of the vessel by means of which it can be lifted into or out of the opening in the platform. A screen 19 is suspended within and below the top of 85 the bucket by hooks 20 which extend over the flange 17. The provision of the screen will prevent loose parts of the machine from passing into the vessel, and becoming lost 90 when the drained oil is emptied from the vessel.

A bracket 20 extends beneath, and parallel with, the bottom of the vessel 16, and is secured to the spaced frame members 10 by 95 upwardly extending arms 21. A rod 22 extends through an opening in the bracket 20 and is arranged to slide vertically therethrough. A vessel engaging member 23 is secured to the upper end of the rod, and a lever 24 is pivoted to the lower end of the rod for moving the supporting member up and down. One of the arms 21 has outwardly extending flanges 25, and a ratchet member comprising bars 26 having a toothed bar 27 secured therebetween, projects downwardly from and is secured between said flanges. The operating lever 24 is pivoted at 28 to the lower end of the ratchet member, and a pawl 29 is pivoted thereon to engage 100 with the teeth 30. Suitable means, such as a pivoted spring pressed hand grip 31 having a connecting member 32 pivoted thereto 105

and to said pawl, is provided to maintain the lever and the vessel support in desired vertical elevation relative to its supporting plate when in engagement.

- 5 It will be observed that my improved device is capable of use in draining pits or with draining platforms such as are now in common use in garages and filling stations and elsewhere, and that it is adapted for 10 use with any type or size of automobile since the movable frame 1 and the carriage 2 can be brought beneath any desired portion of the automobile so as to catch liquid or oil drained from any part thereof. The 15 frame 1 is adapted to move in directions at right angles to that in which the carriage mounted thereon is moved, and hence any desired location of the vessel 18 can be obtained.
- 20 In operation it is only necessary to move the frame 1 along rail 5 until it is beneath the discharge outlet as the automobile or other mechanism containing liquid to be discharged, and then by suitable movement of 25 the carriage to locate the vessel 18 exactly beneath the liquid outlet. When the vessel 18 has been located beneath the liquid outlet, or before it has been located if desired, by pressing down upon the outer end 30 of the handle 24, the rod 22 is moved upward and the member 23 will engage and move the vessel vertically to the desired height in which position it is secured by the spring pressed pawl and ratchet mechanism. 35 When it is desired to lower the vessel the hand grip is pressed toward the handle to release the pawl, whereupon the outer end of the lever can be raised to lower the vessel. After the liquid has been drained into the 40 vessel 16, the vessel may be lifted from its mounting by the handles 18 and emptied of its contents. This vertical adjustment permits the vessel to be adjusted in close proximity to the receptacle which is being 45 drained, which relation is desirable to prevent splashing, and to insure that all of the liquid, while draining, will be caught by the vessel.
- 50 It will be evident from the foregoing description and drawing that my device can be readily and cheaply constructed since practically all of the parts are standard stock material. The angle irons 2, 3 and 10 as well as tracks 5 are standard equipment. Brackets 6, plate 12 and hangers 13 may be quickly formed of flat metal or easily cast if desired. The wheels 4 and 11 are of course standard equipment and the vessel 16 is either a standard stock article 55 or can be easily procured.

Having thus described one form of my invention, what I desire to secure by Letters

Patent is defined in what is claimed, it being understood that various changes or alterations in the exact form of the device shown 65 not amounting to invention are included in my invention, the scope of which is set forth in what is claimed.

What is claimed is:—

1. In a device of the class described, in 70 combination, substantially parallel runways forming a track, a frame having wheels adapted to engage said tracks, a carriage movably mounted on said frame to run at substantially right angles to said track, a liquid receiving receptacle mounted on said carriage, and adjustable mechanism for maintaining said receptacle in any one of 75 a plurality of vertical positions relative to said carriage.

2. In a device of the class described, in combination, a movable carriage, a liquid receiving receptacle mounted with said carriage, mechanism for raising and lowering said receptacle relative to said carriage, and 80 means for securing said mechanism in a position to maintain said receptacle in desired vertical position.

3. In a device of the character described, in combination, a movable carriage, a liquid 90 receiving receptacle mounted in said carriage, a bracket secured to said carriage extending beneath said receptacle, and means mounted in said bracket to support said receptacle in any one of a plurality of 95 vertical positions.

4. In a device of the character described, in combination, a movable carriage, a liquid receiving receptacle extending through an 100 opening in said carriage, a receptacle supporting member mounted with said carriage beneath said receptacle, and a lever pivotally carried by said carriage for moving said supporting member vertically to engage and maintain said receptacle in any one of 105 a plurality of vertical relations relative to said carriage.

5. In a device of the character described, in combination, a movable carriage, a liquid receiving receptacle extending through an 110 opening in said carriage, a receptacle supporting member mounted with said carriage beneath said receptacle, and a lever pivotally carried by said carriage for moving said supporting member vertically to engage and maintain said receptacle in a plurality of 115 vertical relations relative to said carriage, and pawl and ratchet mechanism cooperating with said lever to secure said supporting member in desired vertical position.

In testimony whereof I hereunto affix my signature this 9 day of August, 1923.

JOSEPH H. LOWDEN.
